[57] CLAIM

The ornamental design for a cover for a food container
or the like, substantially as shown.

DESCRIPTION

FIG. 1 is a top perspective view of a cover for a food
container or the like showing my new design;
FIG. 2 is a top plan view thereof;
FIG. 3 is a side elevational view thereof;
FIG. 4 is a bottom plan view;
FIG. 5 is a cross-sectional view taken on line 5—5 of
FIG. 2; and
FIG. 6 is a cross-sectional view taken on line 6—6 of
FIG. 2.
